UNITED STATES PATENT OFFICE.

SUSAN E. BROCK, OF COOPER, TEXAS.

DESIGN FOR A COVER FOR COOKING-RECEPTACLES.

50,645.

Specification for Design.

Patented Apr. 24, 1917.

Application filed November 29, 1916. Serial No. 134,215. Term of patent 3½ years.

To all whom it may concern:

Be it known that I, SUSAN E. BROCK, a citizen of the United States, residing at Cooper, in the county of Delta and State of Texas, have invented a new, original, and ornamental Design for Covers for Cooking-Receptacles, of which the following is a specification, reference being had to the accompanying drawings, forming part thereof.

Figure 1 is a plan view, and

Fig. 2 is a side elevation of a cover for cooking receptacles illustrating my new design.

I claim:

The ornamental design for a cover for cooking receptacles, as shown.

SUSAN E. BROCK.
